UNITED STATES PATENT OFFICE.

ANDREW LAGERGREN, OF ALTOONA, PENNSYLVANIA.

COMBINATION TOOL.

Application filed June 2, 1920. Serial No. 385,908.

To all whom it may concern:

Be it known that I, ANDREW LAGERGREN, a citizen of the United States, residing at Altoona, in the county of Blair and State of Pennsylvania, have invented new and useful Improvements in Combination Tools, of which the following is a specification.

The object of the invention is to provide a machinist's measuring and plotting tool 10 designed particularly for what is known as end shaft work in squaring the ends of shafts, laying off angular sockets and key ways in shafting, determining centers of ellipses as applied to eccentrics and the like 15 where accuracy of adjustment is essential and to this end, the invention consists in the construction and combination of parts of which a preferred embodiment is illustrated in the accompanying drawings in 20 which:—

Figure 1, is a side view of the tool.

Figure 2, is an edge view of the same.

Figures 3, 4 and 5 are sectional views 25 respectively on the planes indicated by the lines 3—3, 4—4, and 5—5 of Figures 1 and 2.

The instrument embodies essentially the parallel bars 10 and 11 connected by the 30 pivotal links 12 which are adapted to be locked to secure the bar 10 in adjusted relation with the bar 11, thumb nuts 13 engaging pivot pins or screws 14 of which the latter are mounted in the bar 10 being employed for this purpose.

Mounted upon the bar 10 is a slide or traveler 15 which carries a graduated gauge bar 16 disposed perpendicularly to the inner edges of both bars 10 and 11. Carried at one end of the main bar 11 is a fork 17 of which 35 the arms are perpendicularly disposed to each other so that the inner edges 18 are at right angles to each other, the apex of the angle being positioned for bisection by the inner edge of the bar 10 when the latter is 40 at the limit of its adjustment toward the bar 11 at which time it abuts the stops 19 or 20 carried terminally by the latter bar.

Also connecting the bars 10 and 11 is a 45 fine adjustment device consisting of a rod 21 slidably fitted in an opening 22 formed diametrically in the swivel bar 23, the latter being formed with a reduced stem extending through the bar 11 and receiving at its lower end a nut abutting the under face of 50 the bar 11, the stem providing a swivel or

pivotal connection of the block or post 23 with the bar 11. The post or block 23 is fitted with a clamp 24 consisting of a cylindrical head disposed axially within the post and formed with a transverse opening 60 through which the rod 21 passes as clearly shown in Figure 4. The head of the clamp is adapted for axial movement in the seat or pocket formed in the post and when drawn toward the upper end of the post effects a 65 clamping engagement on the rod 21 because of bringing the latter against the upper side of the opening 22, the lower side of the opening in the head at that time frictionally engaging the rod 21. Longitudinal movement of the head of the clamp is effected by means of a threaded stem with which the thumb nut engages, the latter bearing on top of the post. It will be evident that when the clamp is loosened, the 70 rod 21 may slide longitudinally through the opening 22 in the post and the latter being swivelly connected with the bar 11, when longitudinal movement of the rod 21 is effected, pivotal movement of the post will 75 ensue. That end of the rod 21 remote from the post is externally threaded and engages a thumb screw or nut 26 which is disposed between guide ears 27 constituting the up- 80 standing element of a U-shaped member 85 pivotally mounted on the bar 10, as clearly shown in Figure 5, this pivotal connection being of the same character as the swivel connection of the post 23 with the bar 11. When the bars 10 and 11 have been adjusted 90 the approximate distance apart, the turning of the nut 26 will secure the fine adjustment desired, this being of course gauged by the 95 graduations on the gauge bar 16.

To effect the approximate or initial adjustment of the two bars, the thumb nut of the clamp 24 is loosened when free sliding movement of the rod 21 with reference to the clamp and post 23 is permitted. After 100 obtaining approximate adjustment, the clamp 24 is tightened and the fine adjustment made as above indicated after which it is maintained by the tightening of the thumb nuts 13.

The instrument has many useful functions in the machinist's work but particularly is it serviceable in laying off squares and other polygons on the end of a shaft. When the bar 10 is disposed against the 105 stops 19 on the bar 11, it extends diametri- 110

cally across any shaft, the end of which may be seated in the crotch of the fork 17. The size of the square or other polygon being determined upon, the bar 10 is then adjusted 5 away from the bar 11 half the width of the square or diameter of the polygon and the inner side of the bar 10 may then be used as a gauge to inscribe that particular side. The gauge bar 16 can be employed to inscribe a 10 line at right angles to the first said line, if desired, or two lines across the diameter may be drawn at angles to each other but within the center of the square and the sides of the square or polygon inscribed around 15 this center.

The inner edge of the bar 11 between the stop 19 and the fork 17 is beveled to provide a ready inscribing or marking edge and may be employed to advantage in many op- 20 erations.

The invention having been described, what is claimed as new and useful is:—

1. A measuring instrument of the type indicated having parallel relatively movable 25 bars, connecting means for operating the same in parallelism, a gauge bar carried by one of said parallel bars for movement longitudinally thereof, and a fine adjustment device connecting said parallel bars and em- 30 bodying a rod having a sliding connection with one of the bars and an adjustable connection with the other.

2. A measuring instrument of the type indicated having parallel relatively movable bars and means for connecting the same, a gauge bar adjustably mounted for longitudinal movement on one of said bars, and a fine adjustment device connecting the bars and consisting of a rod having a threaded portion, a swivel block carried by one of the bars, a clamp carried by the swivel block, the latter and the clamp adjustably connecting said rod, and an adjusting nut mounted on the other bar and engaging the threaded portion of said rod. 40

3. A measuring instrument of the type indicated having parallel bars and links connecting the same, clamping means for securing the means in adjusted relation to the bars, a slide or traveler mounted upon one of the bars and carrying a gauge bar disposed perpendicularly to the adjacent edges of said bars, an armed fork or yoke carried by one of the bars, the bar carrying the yoke being provided with stops limiting the movement of the other bar relative thereto to dispose the inner edge of said other bar in bisecting relation with the angle between the inner edges of said fork or yoke, and a fine adjustment device operatively connected with both bars. 50

In testimony whereof he affixes his signature.

ANDREW LAGERGREN.
